UNITED STATES PATENT OFFICE.

THOMAS J. BOYCE, OF CHICAGO, ILLINOIS.

ROTARY SCRAPER FOR FINISHING ARTIFICIAL DENTURES.

SPECIFICATION forming part of Letters Patent No. 706,013, dated August 5, 1902.

Application filed July 29, 1901. Serial No. 70,057. (No model.)

To all whom it may concern:

Be it known that I, THOMAS J. BOYCE, a citizen of the United States, residing at Chicago, county of Cook, State of Illinois, have 5 invented a certain new and useful Improvement in Rotary Scrapers for Finishing Artificial Dentures; and I do declare the following to be a full, clear, and exact description of the invention, such as will enable others 10 skilled in the art to which it pertains to make and use the same, reference being had to the accompanying drawings, which form a part of this specification.

My invention relates in general to rotary 15 scrapers, and more particularly to devices of this character which are especially adapted for finishing dentures.

In the construction of rotary scrapers of the type referred to previous to my invention the 20 cutting blades or edges and the body portion have been formed integrally, which has necessitated the use of a grade of metal possessing the hardness requisite for the cutting blades or edges. The initial cost, as well as 25 that of frequent sharpening of the cutting edges, has rendered such devices comparatively expensive.

The object of my invention is to provide a 30 rotary scraper of the class referred to in which the cutting or abrading surface and body portion are formed of different materials, so that the former may have the desired hardness, while the latter may consist of any material suitable for supporting and having set 35 cured thereto the cutting-surface.

A further object of my invention is to provide a rotary scraper of the class referred to which will be efficient in use, simple in construction, and inexpensive in manufacture.

40 My invention will be more fully described hereinafter with reference to the accompanying drawings, and in which the same is illustrated as embodied in several convenient and practical forms, and in which—

45 Figure 1 is a side elevational view of one form of my invention; Fig. 2, a transverse section taken on the line 2 2 of Fig. 1; Fig. 3, a view in side elevation of another form of my invention; Fig. 4, a transverse sectional view 50 of Fig. 3; Fig. 5, a transverse section of another embodiment of my invention; Fig. 6, a longitudinal section on the line 6 6 of Fig. 5,

and Fig. 7 a central vertical section of still another form of my invention.

Similar reference characters are used to indicate similar parts in the several figures of the drawings.

My invention consists, essentially, in a rotary scraper for finishing dentures, in which the cutting-surface, which is shown as comprising a series of blades, is formed separately from the body portion and secured thereto in any suitable manner, preferably, however, by so casting the body portion that it will partially surround the cutting-surface and thereby securely unite the cutting-surface and body portion.

Referring more particularly to Figs. 1 and 2, reference-letter A indicates the cutting-surface, which is shown as comprising a series 70 of blades which are partially embedded in the body portion B. The blades may be arranged in any desired relation to each other and to the body portion. For convenience, however, they are shown as extending in straight lines 75 from the enlarged end of the body portion to the opposite end thereof, where they converge to a central point. The cutting-blades are preferably formed thin and of uniform cross-section, so that as they wear down during the 80 use of the device they will continue sharp, and thereby avoid the necessity of resharpening the blades after the device has been subjected to a certain amount of use. The body portion B may be made of any suitable 85 material for supporting and having secured thereto the cutting or abrading surface. The body portion is, however, preferably formed of cast metal, inasmuch as it affords a convenient manner for securing the cutting-surface thereto, the blades being placed in the desired relation to each other and the body portion then cast, so as to partially surround the several blades constituting the cutting-surface. The cutting-blades A may be provided with apertures a, through which the metal of the body portion extends, and thereby 90 secures the blades to the body portion. b indicates a central opening affording 95 means for securing the device to a lathe.

In Figs. 3 and 4 is illustrated another embodiment of my invention, in which the rotary scraper consists in a substantially flat central portion around which is located an annular

projection to which is secured the cutting or abrading surface. In these figures, A' indicates the cutting-surface, shown as consisting of a number of thin cutting-blades, each of 5 which has a perforation a' therethrough. The body portion B' is provided with a central aperture b', by which it may be operatively secured to a lathe. When the body portion is cast, the metal thereof passes through the 10 openings a' in the blades A', thereby firmly securing them transversely across the annular projection of the body portion.

Figs. 5 and 6 illustrate still another embodiment of my invention, in which the cutting- 15 surface A² consists in a series of beveled blades located in close engagement with each other, as clearly shown in Fig. 5. Each of the blades constituting the cutting-surface A² is provided with an opening a², preferably of 20 dovetail shape, into which the body portion B² extends, and thereby securely attaches the blades thereto. b² indicates an opening for affording a convenient attachment to a lathe.

In Fig. 7 I have illustrated another modification of my invention, in which reference-letter A³ indicates the cutting or abrading surface, consisting of a series of thin blades similar to those illustrated in Figs. 1 and 2, such blades being formed with openings a³ 30 therethrough. The body portion B³ partially surrounds each of the blades and passes through the openings a³ therein, thereby securely holding the blades in the desired relative position to each other and to the body portion. b³ b³ indicate openings at either 35 side of the rotary scraper, so that the device may be so secured to the lathe as to rotate it in either direction, according to which of the two openings b³ is used to secure the device 40 to the lathe.

The operation of my invention is as follows: The device is rotated, preferably, by securing it to a lathe, and while it is in motion the denture which is to be finished or 45 any other article which is to be abraded or polished is held in contact with the cutting-surface, which quickly and efficiently finishes the denture. When the cutting-surface consists of a series of uniformly thin blades, 50 preferably of steel, the device may be continued in use without sharpening, as would be necessary if the cutting-surface consisted

of V-shaped projecting edges, such as would be formed were the entire device integral, the cutting edges being produced on the outer 55 surface of the body portion.

While I have described more or less precisely the details of construction of the several embodiments of my invention, I do not wish to be understood as limiting myself thereto, as I contemplate changes in form, the proportion of parts, and the substitution of equivalents, as circumstances may suggest or render expedient without departing from the spirit of my invention. 65

Having now fully described my invention, what I claim as new, and desire to secure by Letters Patent, is—

1. As an article of manufacture, a rotary scraper for finishing artificial dentures consisting in a body portion, and a separate curved cutting-surface secured to said body portion and extending toward the axis of the scraper at an end of the same, substantially as described. 70

2. In a rotary scraper for finishing artificial dentures, the combination with a body portion, of a curved cutting-surface having openings therein into which the body portion extends and thereby securely unites the cutting-surface and body portion, substantially as described. 75

3. In a rotary scraper for finishing artificial dentures, the combination with a series of curved cutting-blades having openings therein, of a cast-metal body portion partially surrounding said blades and extending through the openings formed therein, substantially as described. 80

4. In a rotary scraper for finishing artificial dentures, the combination with a series of semicircular cutting-blades, of a body portion in which said blades are partially embedded said body portion having openings formed therein concentrically with the ends 90 of said blades and at opposite points on its circumference, substantially as described. 95

In testimony whereof I have hereunto subscribed my name in the presence of two subscribing witnesses.

THOMAS J. BOYCE.

In presence of—

GEO. L. WILKINSON,
CLARA C. CUNNINGHAM.
